PACKING AND STORAGE CONTAINER

Samuel Vadner, Narberth, Pa.

Application January 31, 1949, Serial No. 73,755

2 Claims. (Cl. 229—23)

1

This invention has general reference to packing cases or containers usually made, or mainly formed, from fiber-board or like material while it relates more particularly to the species or form thereof suitable for the shipment and temporary storage of bottled products such as beer, for instance.

Packing cases or containers of the species above referred to while measurably successful in many instances are subject to rapid deterioration, easy damage, and consequently unsuited for lengthy service and re-use. Another disadvantage inherent to packing cases or containers of the type referred to is that in the event of damage to the bottled contents, with resultant spillage of liquid thereinto, said cases or containers rapidly become unsanitary and useless.

Accordingly, it is a primary object of my invention to overcome the just above noted disadvantages by providing a novel form of sheet-material packing case or container which can be made of comparatively light-fiber-board, that embodies refinements conducive to ensure added strength and rigidity where needed; which is capable of retaining its intended shape and withstanding rough handling; and that may be reused with safety due to substantial maintenance of its initial strength and durability, while being protected from impairment by internal retention of water, beer or other liquid spillage.

Another object of my invention is to provide an improved packing case or container of the type referred to above, that is readily blanked out of fiber-board and set up with a minimum of material wastage and labor cost.

Further objects of my invention consist in the provision of an improved fiber-board packing case or container characterized by extra strength at the bottom where wear is greatest, that is reinforced in the region of the hand-hole upper and lower surrounding edges, as well as including a superior means for retaining the cover sections or panels in closed position.

While the foregoing definitions are indicative in a general way of the aims of my invention, other objects with ancillary advantages, will be evident to those conversant with the art upon a full understanding of the construction and set up of the means hereinafter fully described; but it will also be appreciated that the invention is susceptible of other embodiments or structurally modified forms coming equally within the terms and scope of the claims.

In the drawings:

Fig. 1 is a perspective view of one practical

2

embodiment of my improved packing case or four piece container having one section of the cover shown in open position, and also with a portion of said case or container broken out and in section to better disclose otherwise hidden structural features.

Fig. 2 is a cross-section taken approximately on the plane designated by the arrows II—II in Fig. 1.

10 Fig. 3 is a partial longitudinal section taken on the plane substantially included between the arrows III—III in Fig. 1.

Fig. 4 is a fragmentary detail lower corner section taken approximately as indicated by the arrows IV—IV in Fig. 1.

15 Fig. 5 is a fragmentary section of an alternate manner of attaching the cover section hinge portions to the ends of the packing case or storage container, which is hereinafter explained.

20 Fig. 6 is a plan view of the fiber-board body blank for the case or container of Figs. 1—4 inclusive.

Fig. 7 is a similar view of a bottom component of the case or container.

25 Fig. 8 is a plan view of one of the cover sections as blanked out of fiber-board.

Fig. 9 is an enlarged detail section taken as indicated by the arrows IX—IX in Fig. 8.

Fig. 10 is a perspective view, similar to Fig. 1, of what I preferably term a three-piece form of my invention.

30 Fig. 11 is a reduced scale plan view of the body blank including the cover, end and a bottom section for the case or container shown by Fig. 10; and,

35 Fig. 12 is a similar scale plan view of duplicate side components therefor.

In describing the forms of my invention exemplified in the accompanying three sheets of illustrative drawings, specific terms will be employed for the sake of clarity, but it is to be understood the scope of said invention is not thereby limited; each such term being intended to embrace all equivalents which perform the same function for an analogous purpose.

40 Referring more in detail to the drawings the form of my improved packing case and storage container, depicted more particularly in Figs. 1—9 inclusive, that I conveniently call for a four part structure, comprising a main or body blank comprehensively designated as 13 in Fig. 6; a bottom blank 14, Fig. 7; and, complementary or 45 duplicate cover member blanks 15 one of which only is shown by Fig. 8. The body blank 13 is formed of any desirable and bendable sheet ma-

terial, such as fiber-board of comparatively thin and light weight character, said blank being provided with a longitudinal crease-line 16 and transverse crease lines 17 that subdivide the blank 13 into a pair of side walls 18, and end walls 19, the outer of the latter including an extension flap 19'; while cut-outs or slits 20 outwardly beyond the longitudinal crease line 16 set apart reinforcing side and end wall edge reinforcing flaps 21, 22 respectively. Particular attention is directed, at this juncture, to the fact that the side wall reinforcing flaps 21 are of approximately quadrilateral formation or have their longer edges, defined by the associated portion of the crease line 16 and their outer edges 23 in parallel, with the respective end edges 24, 25 opposingly inclined at corresponding angles above and below, as shown, the intervening transverse crease lines 17. On the other hand, the end wall reinforcing flaps 22 are of rectangular contour and have medial notches 26 in their respective outer edges 27 which parallel the longitudinal crease line 16 aforesaid. It is also to be remarked that the confronting end edges of the respective reinforcing flaps 21, 22, at their inner ends 28, are equally spaced apart with respect to the adjoining end of the transverse crease lines 17, for reasons hereinafter set forth.

A horizontal hand-opening or hole 29 is provided in each end wall 19 with the three-sided strip, thereby released, having its un-severed region transversely creased at 30 for inward bending at approximately right-angles to the general plane of said end wall to define an abutment flange 31, the purpose whereof will be hereinafter fully explained.

The side wall portions 18 of the body blank 13 are each provided with a centrally located rectilinear opening 32 having in the longer dimension sides medially opposed angular cut-outs 33 which, when the side reinforcing flap 21 is retroverted along the crease line 16, jointly define receiving notches 34 having bevel entrant edges 35, Figs. 1 and 3, for reception of the cover sealing and securing flanges 36, as later on herein further referred to.

The packing case or storage container bottom 14, Fig. 7, is preferably a rectangular blank of stronger or thicker fiber-board than that previously described as constituting the body blank 13, while said blank 14 is provided with right-angled corner cutouts 37 and longitudinal and lateral crease lines 38, 39 respectively. These crease lines 38, 39 it is to be particularly observed, are in parallel relation outwardly of the angular points 40 of the cut-outs 37 so as to define side and end reinforcing flanges 41, 42 respectively, when vertically bent for attachment to the lower parts of the body blank sides 18 and ends 19, as by staples 43.

The cover member or top section blanks 15, Fig. 8, each embody a cover-portion 44 defined by longitudinal and lateral crease lines 45, 46 respectively, such cover-portion 44 including side flanges 47 outwardly of the longitudinal crease lines 45, and said flanges embodying extensions 48 set apart by continuations 46' of the outer lateral crease line 46. Intervening the extensions 48, and separated therefrom by slots 49, is a relatively narrower continuation 50 of the cover portion 44 including a crease line 51, for a purpose hereinafter clarified. In addition to the parts 47, 48 and 50, just described, the blank 15 further includes what I preferably term an "accordion pleated" extension 52 conveniently

although not essentially, subdivided by an appropriate V-section cut-score 53 and a parallel reversely related chain, or rolled, score 54 into relatively retrovertible or collapsible pleats 55, 56 and 57. In addition the continuation 52 is provided with a hand-hole 29', Fig. 8, medially divided between the pleats 55 and 56, as well as an end notch 26'; while it is here emphasized that the cut-score 54, when collapsed, effectively eliminates the formation of any crevice in which roaches or other insects may enter or lodge when the extension 52 is collapsed.

Turning now to the alternative form of my invention, as illustrated by Figs. 10-12 inclusive, and which I conveniently term a three-piece packing case and storage container, only those portions thereof which differ from the corresponding parts of Figs. 1-8 inclusive will be contrastingly designated; whereas the remaining portions will be similarly distinguished by like reference characters with an added prime exponent to obviate the need for unnecessary repetitive description. Briefly stated the main or body blank 13' of Fig. 11 embodies a bottom section 14' which is provided with side flanges 58 only; the end walls 19' having opposed flanges 22' and 63, and the cover components 15' with their associated continuations 50 embodying the side flanges 47' and extensions 48' as well as the accordion-pleated extensions 52' said extensions, however, each embodying an additional pleat 59, while a second cut crease 60 intervenes the pleats 57' and 59 and an additional hand-hole 61 is medially divided between the pleats 57' and 59. It is also to be remarked that in this modified form of packing and storage container I employ but three blanked out components; to wit, the blank 13' just above described, and a pair of duplicate side components, such as the blank 62 of Fig. 12; said blank 62 including spaced creases 16' that define the reinforcing flap 21', and a lower flange 63 above referred to, as well as an opening 32', 33', respectively conforming with the parts 32, 33 of Fig. 6. The lower flap or flange 63 is adapted to underlap the bottom 14' and inturned side flanges 21', 63 of the respective ends 19' for mutual attachment, as by staples 43', in an obvious manner. Incidentally, the lower flap or flange may be dispensed with, and a plain rectangular bottom 14' be inset relative to the sides and ends of the container by providing said sides and ends with underlapping flanges, in an obvious manner. In other words, the sides and ends may have lower edge flaps for stitching or stapling on, or under the bottom 14' in which event the latter would be a rectangular sheet only. It is furthermore to be noted that the end wall portions 19' of the blank 13', Fig. 11, are engageable with the sides 62 when bent along the longitudinal crease lines 16', and are attachable to said sides 62 of Fig. 12, by aid of vertically spaced staples 64, Fig. 10, or otherwise, as deemed expedient and practicable; said sides 62 being provided with the upper and lower relatively bendable flaps or flanges 21', 63', for such purpose. In addition the respective sides 62 are provided with notch-forming holes 32', 33', corresponding with those hereinbefore described in connection with the embodiment of my invention shown by Figs. 1-4.

Referring now to Fig. 5 which shows an alternative manner of attaching the respective extensions cover sections 15 or 15', it will be observed that the related extension 52 embodies but two pleats 65 and 66 which are retrovertible into

hook-like or grooved parallelism by aid of cross-cut score 53 for reception of the reversely retroverted reinforcing upper flap 22 of the associated end wall 19, as readily understood by those conversant with the art, and rigid inter-connection by spaced staples 69.

Having outlined the structural features of my invention the assembly of the embodiments thereof illustrated is briefly as follows: Referring first to the form shown by Figs. 1-4 more particularly, it will be readily understood that the side and end wall flaps 21, 22 are first retroverted and attached to the respective walls 18, 19; whereupon the body blank 13 is bent along the transverse crease lines 17 into rectangular tubulate shape with the lower flap 19a, as viewed in Fig. 6, angularly bent and attached to the remote inner and overlapped edge 18', of the adjoining side 18, Fig. 6, by vertically spaced staples or the like 67, Fig. 1. The bottom 14, with its side and end reinforcing flanges 41, 42 vertically turned, is next applied and secured in place by horizontally spaced staples 43, in an obvious manner. It is to be particularly remarked, at this juncture, that the angular points 40 of the bottom cut-outs 37 are inset relative to the crease lines 38, 39, when the parts 13 and 14 are attached as just set forth whereby small outlets will be provided at each of the case or container bottom corners for the free drainage of any liquid that might be spilled into or otherwise accumulate in said case or container and become soaked-up or saturate the bottom 14. Such provision, I have found, adds little or nothing to the manufacturing cost and greatly increases the durability of my improved bottle packing and storage container. The case and container thus formed is now ready for application thereto of the opposingly opening covers 15, in the following manner. Each said cover 15 first has the opposed side flanges 47 bent over at right angles to the common plane of the part 44, with the extensions portions 48 of said flanges 47 correspondingly and inwardly turned, at the crease line extensions 46', into aligned relation for overlap by retroversion of the continuation 50 along its crease 51, for mutual attachment as by staples 69, in Figs. 1-3. From Figs. 2 and 3 it will be understood that the end extensions 48 not only reinforce the cover sealing or securing flanges 36 when jointly forced into the notches 34 but that they also greatly strengthen the angular corners of the cover as a unit. The pleated extension 52 is next collapsed accordion fashion with the pleats 55, 56 and 57 mutually overlapped, whereupon said extension 52 is seated, by aid of the medial edge notching 26', on the abutment flange 31, see Figs. 1 and 3 to best advantage, when the thus assembled parts are firmly attached together by additional through-staples 70.

The manner of assembling or setting-up the alternative form of packing case and storage container shown by Figs. 1-12 inclusive will be self-evident to those conversant with the art from the foregoing disclosure and, accordingly, further elaboration of the related assembly set-up is deemed unnecessary.

From the foregoing it is felt the merits and advantages of my improved packing and storage container will be clearly understood; also that the interior of said container may be readily equipped with conventional separator partitions to define individual article or bottle holding di-

visions, but such partitions are not shown as they form no part of my invention.

It is also to be noted that by making the "accordion-pleated" connection between the covers 15 and the casing end walls 19 or 19' considerable strength is accorded the container where extra strength is most needed. In addition by making the bottom 14 of extra strong fiber-board provision is made for increased resistivity where wear is greatest; while added strength at the hand-holes 29 or 29' is afforded by my invention. Furthermore, by making the bottom 14, as hereinbefore shown and described it is readily renewable by simply removing the attaching staples 43 and replacing it with a new one when necessary or desirable; while said relatively stronger bottom 14, when stapled or stitched to the sides 18 and ends 19, positively ensures great rigidity and also prevents "sagging" or "bellying" when the container is filled and being lifted or otherwise moved about.

Finally it is to be understood that changes in the details of formation of the several blanks 13, 14, 15, 13' and 62 may be effected to meet different sizes of the container and service conditions without departing from the terms and scope of the following claims.

Having thus described my invention, I claim:

1. A packing and storage container comprising a main or body blank of comparatively thin sheet material provided with a longitudinal crease line and transverse crease lines subdividing said blank into a pair of side walls and a pair of end walls, with one of the latter including an angularly bendable attaching flap; side and end wall-edge flaps outwardly beyond the longitudinal crease line for retroversion into lapping engagement with said side and end walls to reinforce the latter about their upper edges; means for lapping fixture of the end wall attaching flap to the confronting side wall when the blank is bent along the transverse crease lines into tubular form; a rectangular bottom blank of relatively stronger sheet material than that of the body blank having longitudinal and lateral crease lines with corner cut-outs to define side and end attaching flanges; means for removably attaching the bottom blank, to the confronting portion of the tubular formed body blank, for renewal when desirable; a pair of complementary members or blanks each of which embodies a cover portion having side flanges, a free end reinforced flange for retaining the cover portion in closed position, and an opposingly related accordion-pleated continuation, and said continuation when collapsed constituting a reinforced means for attachment to the inner portion of the respective body blank end walls, said body blank being of comparatively thin fiber board wherein each end wall portion includes hand-hole having the upper unsevered region transversely creased and inwardly angled as an abutment flange; and wherein the respective cover blank accordion-pleated continuations include medial notches for seating on the related abutment flange.

2. A packing and storage container comprising a main or body blank of comparatively thin sheet material provided with a longitudinal crease line and transverse crease lines subdividing said blank into a pair of side walls and a pair of end walls, with one of the latter including an angularly bendable attaching flap; side and end wall-edge flaps outwardly beyond the

longitudinal crease line for retroversion into lapping engagement with said side and end walls to reinforce the latter about their upper edges; means for lapping fixture of the end wall attaching flap to the confronting side wall when the blank is bent along the transverse crease lines into tubular form; a rectangular bottom blank of relatively stronger sheet material than that of the body blank having longitudinal and lateral crease lines with corner cut-outs to define side and end attaching flanges; means for removably attaching the bottom blank, to the confronting portion of the tubular formed body blank, for renewal when desirable; a pair of complementary members or blanks each of which 15 embodies a cover portion having side flanges, a free end reinforced flange for retaining the cover portion in closed position, and an opposingly related accordion-pleated continuation, and said continuation when collapsed constituting a reinforced means for attachment to the inner portion of the respective body blank end walls, wherein the accordion-pleated continuation is

10 5

provided with a transverse cut score, and a parallel reversely related chain or rolled score to define opposingly collapsible pleats.

8 SAMUEL VADNER.
